UNITED STATES PATENT OFFICE.

JOHN W. CARNOCCHAN, OF SILVERCREEK, NEW YORK, ASSIGNOR TO HUNLEY MANUFACTURING COMPANY, OF SILVERCREEK, NEW YORK.

CAN-FILLING MACHINE.

SPECIFICATION forming part of Letters Patent No. 735,209, dated August 4, 1903.

Application filed October 10, 1902. Serial No. 126,704. (No model.)

To all whom it may concern:

Be it known that I, JOHN W. CARNOCCHAN, a citizen of the United States, residing at Silvercreek, in the county of Chautauqua and State 5 of New York, have invented new and useful Improvements in Can-Filling Machines, of which the following is a specification.

This invention relates generally to can-filling machines, but more particularly to a machine for filling cans with string-beans.

The principal object of my invention is the construction of a simple machine of this kind by which a gang of cans may be effectually shaken both laterally and vertically, so as to 15 quickly and uniformly fill the same.

A further object of the invention is to improve the construction of the box or table which supports the cans with a view of facilitating the insertion and removal of the cans.

20 In the accompanying drawings, consisting of two sheets, Figure 1 is a side elevation of my improved machine. Fig. 2 is a vertical longitudinal section of the same. Fig. 3 is a transverse section in line 3 3, Fig. 1. Fig. 4 is a top plan view of the machine.

Similar letters of reference indicate corresponding parts throughout the several views.

A indicates the stationary frame of the machine, and B a vibratory box or table arranged 30 lengthwise within the upper portion of the frame. This box is supported near each end by a pair of upright rods C, provided at their lower ends with straps D, which surround rotary eccentrics D'. The latter are secured to 35 transverse shafts d, journaled in bearings on the lower longitudinal members of the frame. The upper ends of the eccentric-rods C are pivoted by transverse pins e to lugs E, secured to the under side of the box B near its 40 ends. The two shafts are turned in the same direction and at the same speed by any suitable mechanism; but the eccentrics on one of these shafts are set a half-turn in advance of those on the other, so that as the box is raised 45 at one end by one set of eccentrics it is lowered at the opposite end by the other set, thus rocking it at both ends. In the construction shown in the drawings the eccentric-shafts are geared together by sprocket-wheels f f' 50 and a sprocket-chain f'', and motion is transmitted from a driving-shaft G to one of the

eccentric-shafts by a similar chain g and wheels g' g''. The main driving-shaft is arranged transversely at one end of the frame A and above the plane of the eccentric-shafts 55 d. The chains f'' and g may be provided with suitable tighteners h h', as shown.

In addition to being rocked in a vertical direction at both ends the box B is reciprocated or shaken lengthwise by any suitable means, 60 the mechanism shown in the drawings consisting of a pair of eccentrics I, secured to the driving-shaft G, and longitudinal connecting-rods I', pivoted at their inner ends to the box and provided at their outer ends with straps 65 i, which encircle said eccentrics. These eccentrics and rods also serve to steady the box B by connecting the same with the stationary frame. By supporting the box upon the upright rods C clear of the frame and connecting 70 the same with the frame by such a movable steadyng device guides or other separate attachments for this purpose are dispensed with, thus simplifying the construction of the machine. By this construction the upright 75 supporting-rods C also operate with less friction than rods or bars which slide in guides on the stationary frame, thus enabling the machine to be driven with less power.

J indicates a removable tray arranged in 80 the lower portion of the box B and adapted to receive a gang of cans K to be filled. This tray preferably consists of a drawer, which is slid endwise through an opening at one end of the box and held in place during the operation of the machine by turn-buttons l or other suitable means. Within the box above this can tray or drawer is arranged a feed-hopper M for the string-beans or other material to be delivered into the cans. This hopper is provided in its bottom with rows of discharge-openings m, which are arranged to register with the openings of the cans, respectively, as seen in Fig. 3, so that the material is fed into the cans by the shaking motion of the 85 box B in a manner common to this class of machines. The feed-hopper preferably consists of a shallow metallic box, which is removably secured in the upper portion of the main box B by bolts and thumb-nuts n, as 90 shown, or by other appropriate fastenings. This construction permits the hopper to be 95 100

readily removed for conveniently cleaning it and the box.

In the use of the machine the can tray or drawer is withdrawn from the box B and after filling it with cans is replaced and secured by the turn-buttons l. The hopper is then filled with the desired material and the machine set in motion. The actuating mechanism rocks the box B up and down alternately at opposite ends and simultaneously vibrates the same in a longitudinal direction, vigorously shaking the cans both up and down and sidewise and causing the material delivered into the cans to settle quickly, uniformly, and compactly in all of the same. After filling the cans the tray J is withdrawn, emptied, refilled with another gang of cans, and replaced, and a fresh charge of material is delivered into the feed-hopper.

The inner ends of the upper connecting rods I' are preferably connected with the under side of the box B midway of its ends, as shown, and the corresponding eccentrics which shake the box longitudinally are so set relatively to the lower eccentrics D' that each end of the box is caused to descend as it advances and to ascend as it recedes, thereby obtaining the maximum shaking effect of the eccentrics. As the box is rocked at both ends, the cans in its central portion receive less vertical motion than those near its ends; but by imparting a longitudinal reciprocating motion to the box in addition to its rocking motion the reduced vertical vibration of the central cans is largely compensated for by the lateral shaking of the cans, due to the reciprocating motion of the box. The two sets of eccentrics D' I, while imparting a compound rocking and reciprocating motion to the box B and its contents, are smooth and noiseless in action.

I claim as my invention—

1. In a can-filling machine, the combination of a frame, a vibratory table or support for the cans, a feed-hopper carried by the table and having openings through which the material passes into the cans, and actuating mechanism constructed to reciprocate the table longitudinally and at the same time rock the same vertically at both ends, substantially as set forth.

2. In a can-filling machine, the combination of a stationary frame, a vibratory table or support for the cans, a feed-hopper mount-

ed on the table and having openings through which the material passes into the cans, horizontal shafts supported on the frame below said table and carrying eccentrics, upright supporting-rods having their upper ends pivotally connected with the table and provided at their lower ends with straps which encircle said eccentrics, and a movable steady device connecting said table with the stationary frame, substantially as set forth. 65

3. In a can-filling machine, the combination of a frame, a vibratory table or support for the cans, a feed-hopper mounted on the table and having openings through which the material passes into the cans, transverse shafts supported on the frame below the ends of the table and provided with eccentrics, upright rods having their upper ends pivotally attached to the end portions of the table and provided at their lower ends with straps which embrace said eccentrics, a third transverse shaft supported on the frame opposite one end of the table and above the plane of the first-named shafts, and an eccentric and a connecting-rod for transmitting motion from the last-named shaft to the table, substantially as set forth. 70

4. In a can-filling machine, the combination of a frame, a vibratory table or support for the cans, a feed-hopper mounted on the table and having openings through which the material passes into the cans, transverse shafts supported on the frame below the ends of the table and provided with eccentrics, upright rods having their upper ends pivotally attached to the end portions of the table and provided at their lower ends with straps which embrace said eccentrics, a third transverse shaft supported on the frame above the plane of the first-named shafts and provided with an eccentric, and a connecting-rod having one end pivotally attached to the table between said upright connecting-rods and provided at its opposite end with a strap which embraces the last-named eccentric, 80 substantially as set forth. 90

Witness my hand this 1st day of October, 1902.

JOHN W. CARNOCHAN.
